UNITED STATES PATENT OFFICE.

MAX RACHLIN, OF NEW YORK, N. Y., ASSIGNOR OF ONE-HALF TO SAMUEL M. GOLD.

WINDOW PROVISION-BOX.

1,401,816.

Specification of Letters Patent. Patented Dec. 27, 1921.

Application filed April 26, 1920. Serial No. 376,814.

To all whom it may concern:

Be it known that I, MAX RACHLIN, a citizen of Russia, and a resident of New York, in the county of Kings and State of New York, have invented certain new and useful Improvements in Window Provision-Boxes, of which the following is a specification.

The present invention relates to provision-safes, and more particularly to that type which is adapted to be attached to a window frame or the outer surface of a wall adjacent a window frame.

One of the objects of the invention is to provide a provision-safe of this character which is adapted to be mounted adjacent a window opening in such a manner as not to interfere with the admission of light and air into the room.

Another object of the invention is to produce a provision-safe which is simple in construction, efficient in operation, and which is adapted for manufacture on a commercial scale, or in other words one which is not so difficult to make as to be beyond the reasonable cost of such an article.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

One of the many possible embodiments of the invention is illustrated in the accompanying drawings, in which:—

Figure 1 is a transverse vertical section taken through a portion of a window frame with the provision-safe, forming the subject matter of the present application, mounted thereon; Fig. 2 is a transverse vertical section taken through the provision-safe, on a larger scale; and Fig. 3 is a section taken on line 3—3 of Fig. 2.

In the drawings the numeral 10 indicates a window frame of any suitable construction, in which the sashes 11 are slidably arranged in the usual manner. The sill 12 of the frame rests on the building wall 13, and to the said sill is fastened the provision-

safe 14, in a manner hereinafter to be described.

The provision-safe is made in the form of a box-like receptacle, the size of which varies according to the requirements, its material being selected so as to give a light construction. The receptacle comprises an outer box 15 and an inner box 16, which are suitably spaced, thereby providing a double-walled construction. The outer box consists of a front wall 17, a rear wall 18, sides 19, 19, and a bottom piece 20. In a similar manner consists the inner box of a front wall 21, a rear wall 22, sides 23, 23, and a bottom piece 24. The corresponding elements of the two boxes are disposed in parallel relation and are spaced one from another, the upper edges of the front and rear walls and sides of the two boxes being connected by a frame 25, whereby a closed space is formed between the two boxes. The upper edges of the sides of the two boxes slant from their front walls toward their rear walls, as clearly appears from Figs. 1 and 2 of the drawings, the top or lid 26 of the safe sloping correspondingly. The lid is pivoted at 27 to the upper or free edge of the rear wall 18 of the outer box, and is provided with a downwardly projecting flange 28 at its opposite longitudinal edge and with similar flanges 29 along its transverse edges. These flanges overhang the corresponding sides of the outer box. The hinged edge of the lid projects beyond the rear wall 18 of the outer box, abutting against the said rear wall when the lid is swung into open position. On the lid of the safe is built a hollow upwardly projecting structure 30, in alignment with which are formed apertures 31 in the lid, said hollow structure being provided in its sides with apertures 32. The apertures 31 and 32 permit of a continuous ventilation of the provision-safe.

Holes 33 and 34 are formed in the bottom piece 20 and the sides 19, respectively, of the outer box, thereby permitting a circulation of air through the space between the two boxes.

A handle 35, in the form of a knob, is attached to the structure 30, to facilitate the opening and closing of the lid of the safe.

To the front wall 17 of the outer box are attached brackets 36, by which the safe is fixed in position upon the window frame. These brackets include each a forwardly projecting horizontal portion 37, from

which extends upward a vertical section 38. The vertical sections 38 abut against the sill 12, while the horizontal portions 37 rest on the building wall. In the vertical sections 38 are provided holes 39, through which extend screws 40 into the sill. The safe abuts against the outer face of the building wall, as clearly shown in Fig. 1 of the drawings.

When it is desired to remove some or all of the articles from the safe, or to replenish the supply, the lower window sash is raised and the lid 25 of the safe swung around its hinges into substantially vertical position, in which its hinged longitudinal edge rests against the rear wall 18 of the outer box 15. Inasmuch as a continuous circulation of air takes place through the holes 33 and 34, the closed space between the two boxes constitutes a refrigerating chamber.

20 What I claim is:—

A window provision-safe, comprising an

outer receptacle, an inner receptacle spaced therefrom, a frame connecting the upper edges of said receptacles so as to provide a single closed space therebetween, said frame serving also to space said receptacles, a lid hinged to one of the upper edges of said outer receptacle, and downwardly projecting flanges on the free edges of said lid overhanging the walls of said outer receptacle, the hinged edge of said lid projecting beyond said receptacle and being adapted to abut against the respective wall of said outer receptacle when said lid is in open position, the bottom and certain walls of said outer receptacle being provided with apertures.

Signed at New York, in the county of New York and State of New York, this 18th day of March, 1920.

MAX RACHLIN.
